UNITED STATES PATENT OFFICE

156,833

ANIMAL PROD

John Juergens, McHenry, Ill., assignor to Leterstone Sales Co., a corporation of Illinois

Application October 29, 1948, Serial No. 149,373

Term of patent 14 years

(Cl. D12—2)

To all whom it may concern:

Be it known that I, John Juergens, a citizen of the United States, residing at McHenry, in the county of McHenry and State of Illinois, have invented a new, original, and ornamental Design for an Animal Prod, of which the following is a specification, reference being had to the accompanying drawing, forming part thereof.

I claim:

The ornamental design for an animal prod, as shown.

JOHN JUERGENS.
